UNITED STATES PATENT OFFICE.

IRVING A. TAYLOR, OF WORCESTER, MASSACHUSETTS, ASSIGNOR TO RILEY STOKER CORPORATION, OF WORCESTER, MASSACHUSETTS, A CORPORATION OF MASSACHUSETTS.

DUAL-FEEDING APPARATUS.

Application filed November 10, 1926. Serial No. 147,587.

This invention relates to feeding devices, and more particularly to an apparatus capable of feeding two different materials simultaneously.

Such an apparatus is often useful in connection with pulverizers of the so-called unit type, in which coal is pulverized and then delivered directly to a furnace for combustion. It is difficult to burn anthracite in this manner, because of its low percentage of volatile matter and the consequent low rate of flame propagation. This trouble can be overcome by mixing with the anthracite a certain amount of bituminous coal, which has a much higher percentage of volatile matter. As a further consideration, a shipment of coal is occasionally received which contains so much moisture as to make satisfactory pulverization impossible. By feeding some dry coal into the pulverizer with the wet coal, no difficulty is experienced. It is therefore desirable to have a feed mechanism which is capable of delivering such different materials satisfactorily. It is essential that the feed be uniform, as any irregularity will cause the flame to fluctuate. Moreover it is important to provide means for regulating the rate of feed, as the demand for heat from the furnace being fired may vary.

Anthracite is ordinarily purchased for power use in small sizes only. Bituminous coal, on the other hand, frequently contains large lumps, and it has been necessary in the past to subject it to a preliminary crushing operation before feeding it to a pulverizer. The expense of crushing such coal in a separate operation is a material item in power plant costs, and a feeder which will handle the ordinary run of coal satisfactorily is much to be desired.

It is accordingly the main object of this invention to provide an apparatus which will feed two materials efficiently and uniformly at desired rates.

Another object is to provide a simple compact type of feeding apparatus which will feed and mix two materials in regulatable proportions.

A further object is to provide a feeding apparatus which will serve to crush coarse material and feed it at a regulatable rate.

A still further object is to provide such

an apparatus which will not only feed two different materials at desired rates but will serve to crush one of the materials to suitable size for feeding efficiently and uniformly.

With these and other objects in view, as will be apparent to those skilled in the art, this invention resides in the combination of parts set forth in the specification and covered by the claims appended hereto.

In accordance with my invention, I provide an apparatus which will feed different materials simultaneously, and preferably at regulatable rates, and which is so constructed as to insure a uniform rate of feed of each material. I also provide a device which will serve to break any lumps of material found in one of the hoppers.

My preferred construction to accomplish these ends comprises two hoppers, one arranged within the other, which are relatively movable so as to minimize the tendency for the material to arch over one of the outlets. In order to feed the materials at uniform rates from the hoppers, I may provide for each hopper a table and a scraper, which are relatively revoluble and are so arranged as to cause material to be swept from the table into a suitable discharge opening.

Since there may be lumps in one of the materials that would interfere with the feeding operation, these may be crushed preliminarily, and this may be accomplished by a crushing device located at the outlet of the hopper. My preferred construction comprises crushing members on the opposed walls of the relatively movable hoppers, and may include an eccentric portion on the rotatable member capable of breaking the lumps between it and the stationary hopper.

The specific construction illustrated comprises an inner hopper arranged above a horizontal table and connected thereto. An outer hopper surrounds the inner hopper and delivers material to a horizontal annular portion on the inner hopper which serves as a feed table. The two hoppers are relatively rotatable about a vertical axis, and two scrapers are arranged to remove material from the horizontal table and the annular portion. These scrapers are preferably adjustable. An eccentric portion on the outside of the rotatable hopper and near the

bottom is provided with a corrugated surface which serves to produce a crushing action on the material being fed from the outer hopper.

5 Referring to the drawings, in which like reference numerals indicate like parts:

Fig. 1 is a vertical section through one embodiment of my invention, the section being taken on the line 1—1 of Fig. 2;

10 Fig. 2 is a section on the line 2—2 of Fig. 1, certain parts being shown in full for clearness of illustration;

Fig. 3 is a section through the inner hopper on the line 3—3 of Fig. 1; and

15 Fig. 4 is a detail showing the method of connecting the control levers to the scrapers.

As illustrated in the drawings, one embodiment of this invention may comprise an inner cylindrical hopper 10 surrounded by 20 an outer annular hopper 12 which flares outwardly and upwardly, as shown. It is desirable to provide for relative motion between the hoppers, to assist in feeding material from the outer hopper. This may be 25 accomplished by mounting the hopper 12 on the stationary casing 14, and rotating the hopper 10 about a vertical axis. For this purpose, the hopper 10 is provided with radial arms 15 which are supported on a central hub 16. The hub is bored to fit a reduced portion on a vertical post 18, and is attached thereto by key 20 and cap screw 21. The post 18 is in turn threaded, for purposes of assembly, on the end of a shaft 22 which 30 is mounted in suitable bearings 23 and 24. This shaft may be rotated by any desirable means, such as worm gear 26 and worm 28, the latter being connected to a suitable source of power.

40 On the lower end of the rotatable hopper 10, I provide a horizontal annular portion or shelf 30 which projects outwardly and is arranged to receive material from the stationary hopper 12. A horizontal disk or 45 table 32 arranged to receive material from the hopper 10 is mounted on a reduced portion on the upper end of shaft 22 and is held in place by the post 18 which engages its top surface and serves as a clamping nut.

50 The annular portion 30 and table 32 rotate together, and in order to sweep the material therefrom, I provide scrapers 34 and 35 which project in the path of the revolving material and deflect the outer annular portions thereof and cause them to fall over

55 the edges of the tables and into a suitable chute 36 provided for that purpose. It will be observed that each table projects sufficiently beyond the lower ends of its hopper

60 so that the material may lie thereon at its natural angle of repose, and the casing wall 14 substantially contacts with the outer edge of each table except where it flares outwardly to form chute 36, as shown in Fig. 2.

65 These scrapers are preferably adjustable,

and for this purpose they may be pivotally mounted on the casing 14 and connected to control levers 38 and 40. As shown in Fig. 4, lever 38 and scraper 35 are attached by set screws 42 and 43 to a solid shaft 45. Lever 40 and scraper 34 are attached by set screws 46 and 47 to a sleeve 50 surrounding the shaft 45. A lever sector 52 is mounted on the casing, and the levers may be clamped at any desired position by means of screws 54 and 55.

70 In order to crush the lump material in the hopper 12, I may provide lugs or corrugations 60 and 61 on the opposed surfaces of the inner and outer hoppers, as shown, 80 and the inner hopper has an eccentric portion 64 which varies the size of the outlet as it revolves. In this way, large particles will be crushed between the outer hopper and the eccentric corrugated surface on the inner hopper. Also the tendency for material to bridge over and fail to feed from the outer hopper will be overcome by this arrangement.

85 The operation of this device will now be 90 apparent from the above disclosure. Coal or other material is placed in the hoppers 10 and 12, whence it flows on to the table 32 and the annular portion 30 respectively. The shaft 22 is rotated by a suitable source 95 of power connected to worm 28, and material is swept into chute 36 at a desired rate by the scrapers 34 and 35. The material in the outer hopper is continuously agitated by the relative motion between the rotating 100 and stationary hopper walls. This serves to prevent the material from arching over the outlet and thus hindering the feeding operation, as is the tendency with wet coal. If

105 lumps are present in the outer hopper, they are caught between the corrugated crushing members on the hoppers and broken to a smaller size. This crushing action is made possible by rotating one of the hoppers. The material in each hopper is supported 110 on the table beneath, and only that amount falls into chute 36 as is determined by the positions of the adjustable scrapers. The outlet from the outer hopper is of small size and the crushing members are so arranged that no lumps can clog the opening in which the scraper is located. Moreover, each scraper is made to taper downwardly 115 towards its nose so that lumps will be less likely to obstruct the opening. The rate of feed depends upon the rate of rotation of the shaft 22 and the position of the scraper, either of which may be regulated as desired.

120 It will be apparent to those skilled in the art that this invention provides a feeding apparatus, by which two materials may be fed simultaneously at desired and uniform rates and lumps in one of the materials crushed to a smaller size, and that this device 125 is useful for various materials other than 130

fuel and particularly where two materials, such as ores or chemicals, are to be mixed in regulatable proportions.

Having thus described my invention, 5 what I claim as new and desire to secure by Letters Patent is:

1. A dual feeding apparatus comprising two relatively rotatable hoppers for separate materials, one of which surrounds the 10 other, and means cooperating with each hopper to feed the material delivered therefrom at desired rates, said parts being so constructed and arranged that the relative movement between the hoppers aids in discharging the material from the outer hopper.

2. A feeding device comprising an inner and an outer hopper which are relatively rotatable, an annular shelf beneath the outer 20 hopper positioned so as to receive material therefrom, a table arranged beneath the inner hopper to receive material therefrom, and means for deflecting material from said annular shelf and said table.

25 3. A feeding device comprising an inner rotatable hopper, an outer stationary hopper, a rotatable annular shelf beneath the outer hopper to receive material therefrom, a rotatable disk beneath the inner hopper 30 to receive material therefrom, and means for deflecting material from said shelf and said disk to feed the same.

4. A feeding device comprising an inner rotatable hopper connected to and arranged 35 above a horizontal table, an outer stationary hopper arranged to deliver material to an annular shelf on the inner hopper, and adjustable stationary scrapers to deflect material from said table and said shelf.

40 5. A feeding apparatus comprising a rotary device arranged to feed two materials simultaneously and means cooperating therewith to crush one of the materials before it is fed.

45 6. A feeding apparatus comprising two feed tables and an inner and an outer hopper discharging material thereon, said hop-

pers being relatively movable and so constructed and arranged that lumps of material in the outer hopper are crushed 50 before they are delivered therefrom.

7. A feeding apparatus comprising an inner and an outer hopper, one of which is stationary and the other rotatable, a feeding device cooperating with each hopper 55 to feed material discharged therefrom, and means on the opposed walls of the hoppers to crush lumps of material as they are discharged from the outer hopper.

8. A feeding device comprising an inner 60 and an outer hopper which are relatively rotatable, an annular shelf on the inner hopper arranged to receive material from the outer hopper, a disk beneath the inner hopper to receive material therefrom, means for 65 deflecting material from said shelf and said disk, and corrugations on one of said hoppers adjacent to the other hopper to aid in crushing lump material.

9. A feeding device comprising an inner 70 and an outer hopper which are relatively rotatable, an annular shelf on the inner hopper arranged to receive material from the outer hopper, a disk beneath the inner hopper to receive material therefrom, means for 75 deflecting material from said shelf and said disk, and an eccentric portion on one of said hoppers to aid in crushing lump material.

10. A feeding device comprising a rotatable hopper, a stationary hopper surrounding the same and having a constricted annular outlet, two rotatable tables beneath and arranged to receive the material discharged from the hoppers, an adjustable 85 scraper cooperating with each table to deflect the material and feed it therefrom, and crushing members on the opposed hoppers within said outlet arranged to break the lumps of material passing from the outer 90 hopper.

Signed at Worcester, Mass., this 8th day of November 1926.
